CODE RESPONSIVE CONTROL APPARATUS

Charles C. Buchanan, Wilkinsburg, Pa., assignor
to The Union Switch & Signal Company, Swiss-
vale, Pa., a corporation of Pennsylvania

Application May 31, 1940, Serial No. 337,977

13 Claims. (Cl. 246—34)

My invention relates to code responsive control apparatus; and it has particular reference to code responsive control apparatus of the class employed in railway traffic controlling systems utilizing coded energy of the frequency code type for controlling either or both wayside signals and train-carried cab signals.

Railway traffic controlling systems of the above described class are characterized by the fact that such systems utilize code responsive control apparatus operated by energy received from a pair of conductors, for selectively controlling traffic governing devices in accordance with the rate at which energy received from the conductors is coded; and the code rate at which such energy is supplied to the conductors is controlled by traffic conditions in advance. Generally speaking, the supply of energy to the conductors, which may be the rails of the trackway, is periodically interrupted or coded at one or another of a plurality of code rates through the medium of a code transmitter or coding device; and the code responsive control apparatus establishes selective control over its associated traffic governing device through the medium of decoding apparatus including circuits arranged and tuned to be resonant at one or another of the code rates at which energy is supplied from the code responsive apparatus to such circuits. In such systems, it has been found desirable on the one hand to code or interrupt the supply of energy to the two conductors at relatively low code rates, thereby avoiding pitting and undue wear of the contact structures incorporated in the code transmitters which code the supply of control energy, while on the other hand it has been found desirable to supply energy to the code responsive apparatus coded at relatively high code rates in order to utilize relatively small and inexpensive tuning and decoding units for detecting the various rates at which such energy is coded.

I am aware that various code responsive means have been proposed heretofore for increasing the rate at which energy is supplied to the decoding apparatus in response to the relatively low code rates at which energy is received from the pair of conductors. However, in all such systems heretofore proposed that I am aware of, moving mechanical parts are employed for intermittently making and breaking circuit controlling contacts at an increased rate proportional to the received code rate. Such apparatus is, therefore, subject to wear and pitting due to high speed operation of the control contacts, and is subject to failures due to the breaking or sticking of the mechani-

cally moving parts. In view of the above-mentioned and other important considerations, it is an object of my invention to provide novel and improved code responsive control apparatus operated by energy coded at low code rates and incorporating means utilizing no moving mechanical parts for multiplying or increasing the code rates at which such apparatus supplies energy to its associated decoding apparatus. 5

An additional object of my invention is the provision of novel and improved railway traffic controlling apparatus of the class operated by coded energy of the frequency code type.

A further object of my invention is the provision of novel and improved code responsive control apparatus of the class adapted for use in control systems selectively operated by coded energy.

The above-mentioned and other important objects and characteristic features of my invention which will become readily apparent from the following description, are attained in accordance with my invention by providing a control system employing code responsive apparatus of the saturation type in which the supply of energy 20 from a source of alternating current to an output winding disposed on a magnetizable core is controlled in accordance with the state of magnetic flux in such core, and the magnetic condition of such core is controlled by a biasing 25 winding constantly supplied with unidirectional current for setting up a given condition of flux of one polarity in the core, and by a control winding supplied with coded control energy from a pair of conductors and effective upon such supply for creating magnetic flux in the core of the opposite relative polarity and of such magnitude that a resultant flux of the opposite relative polarity is set up in the core. In other words, I provide a saturation type code responsive control device wherein the state of flux in the magnetizable core is carried from a given flux condition through a zero or no flux condition to a substantially equivalent flux condition of opposite relative polarity both on the supply of energy to 45 the control winding and when such supply is interrupted, whereby the supply of current from the output winding of the device is caused to be coded at a rate twice the code rate at which energy is supplied to the control winding. 50

I shall describe one form of apparatus embodying my invention, and shall then point out the novel features thereof in claims.

In the accompanying drawings, Fig. 1 is a diagrammatic view illustrating a preferred form 55

of apparatus embodying my invention. Fig. 2 is a graphical representation illustrating a typical form of control energy which may be used in conjunction with the apparatus of Fig. 1. Fig. 3 is a graphical representation which illustrates such control energy rectified into unidirectional energy, and which also represents the flux created in the core of device SR, shown in Fig. 1, due to the supply of such rectified energy to control winding 18 of the device. Fig. 4 is a graphical representation illustrating the biasing flux normally present in the core of device SR. Fig. 5 is a curve representing the varying resultant flux conditions in the core of device SR caused by the intermittent supply of control energy and the constant supply of biasing energy to such device. Fig. 6 is a curve representing the effective current supplied from output winding 16 of device SR in response to the intermittent supply to such device 20 of control energy of the type represented in Fig. 2.

Referring to Fig. 1, the reference character X designates a stretch of railway track over which traffic normally moves in the single direction indicated by an arrow in the drawings, and over 25 which traffic movements are controlled by means of control apparatus embodying my invention and presently to be described in detail. The protected stretch of track X is provided with a pair of conductors to which coded energy of the 30 frequency code type is supplied for controlling traffic governing apparatus in accordance with the rate at which such energy is coded. As shown, the two conductors comprise the two track rails 1 and 1a of the stretch of track, which 35 rails are divided by means of the usual insulated rail joints 2, as is the usual practice, into a plurality of successive adjoining track sections, only one section of which, D—E, is shown complete in the drawings.

40 Coded control energy is supplied to the rails 1 and 1a of section D—E adjacent exit end E of the section, for selectively controlling suitable apparatus, later to be described, in accordance with the rate at which such energy is 45 coded. As shown, the rails 1 and 1a are supplied with alternating energy from a suitable source of alternating current such, for example, as a generator not shown but having its opposite terminals designated in the drawings by the reference characters BX and CX. This energy is 50 periodically interrupted or coded at one or another of the customary plurality of low code rates utilized in railway signal systems, by means of a coding device or code transmitter CT. The 55 device CT may take any one of many well-known forms but is illustrated as comprising a plurality of rotatable cams each designated by the reference character K with a distinguishing suffix. The cams K are driven at a constant speed of, 60 say, 15 revolutions per minute by a motor M which is constantly supplied with alternating current so that the coder is continuously active. Each of the cams K is provided with a different 65 number of teeth or projections spaced about its periphery, which teeth successively operate an associated contact member to close periodically a circuit controlling contact as the cam is rotated. For example, cam K1 is shown provided with twelve teeth or projections, each of which 70 successively engages a contact member 1 to close periodically a circuit controlling contact 1—8. Similarly, cam K2 is shown provided with eight teeth, each engaging an associated contact member 9 to close periodically contact 9—10; and 75 cam K3 is shown provided with five teeth each

engaging an associated contact member 11 to close periodically a circuit controlling contact 11—12.

In accordance with certain predetermined conditions, one or another of the above-mentioned contact members operated by coder CT is conditioned to interrupt periodically or code the supply of trackway energy to the rails of section D—E. As indicated in the drawings, the control of such trackway energy may be established by suitable apparatus responsive to traffic conditions on the stretch in advance of section D—E. The details of the traffic controlled apparatus controlling the supply of trackway energy are not shown in the drawings since they form no part of my present invention, but such apparatus may comprise the usual decoding relays, such as relays H, BJ and AJ hereinafter referred to, controlled by traffic conditions in advance of section D—E through the medium of code 20 responsive apparatus such as will be hereinafter described, and which relays set up or establish one or another of a plurality of circuits over which energy is supplied to the primary winding of a track transformer TT, which transformer has its secondary winding connected, in series with the usual current limiting impedance 5, across the track rails 1 and 1a adjacent exit end E of section D—E. As is readily apparent from an inspection of Fig. 1, one of the plurality of circuits above mentioned includes contact 1—8 of coder CT and since this contact is operated by each of the twelve teeth of cam K1 of coder CT, energy flowing in such circuit is periodically interrupted or coded at a rate of 35 180 interruptions per minute. The second of the plurality of circuits includes contact 9—10 of coder CT, which contact is operated by each of the eight teeth of cam K2 and hence energy flowing in this circuit is periodically interrupted 40 at a rate of 120 times per minute. A third of the plurality of circuits shown includes contact 11—12 of coder CT, which contact is operated by each of the five teeth of cam K3 and as a 45 result energy flowing in this circuit is periodically interrupted some 75 times per minute.

I have represented graphically in Fig. 2 the form of control energy of the frequency code type that is supplied to the rails 1 and 1a over a typical one of the abovementioned plurality of 50 circuits. For example, Fig. 2 represents the current flow of the 120 code, in which the "on" periods during which energy flows when contact 9—10 of coder CT is closed are represented by 55 illustrating several successive cycles of alternating current, while the "off" periods during which no energy flows when contact 9—10 of coder CT is open are represented by indicating an absence of such alternating current. It is to be noted that the flow of energy in the circuit in which contact 9—10 of coder CT is interposed, causes control code of the frequency code type to be supplied to the rails of section D—E, which control code is characterized by 60 the fact that the "on" and "off" intervals are 65 substantially equal in duration.

Referring to Fig. 1 once more, I have represented the code responsive control apparatus embodying my invention incorporated into a wayside signaling system for selectively controlling 70 a wayside signal S in accordance with the rate at which energy supplied to the track rails is coded. The wayside signal S preferably is located in the trackway adjacent the entrance end D of section D—E, and may take any one of 75

many well-known forms, but as shown comprises a four-indication color light type signal having a green signal unit G, a yellow over green signal unit Y/G, a yellow signal unit Y and a red signal unit R, which units when illuminated indicate "clear," "approach medium," "approach" and "stop," respectively.

Selective control of the aspects displayed by signal S is effected in accordance with the rate at which energy supplied to the rails 1 and 1a is coded, by means of code responsive apparatus embodying my invention and operated by energy derived from the two track rails of section D—E. As shown, such apparatus comprises a novel form of code responsive control device of the saturation type, designated as a whole by the reference character SR; a decoding transformer DT supplied with energy from device SR; and the usual code detecting and code selecting relays H1, BJ1 and AJ1 controlled by energy supplied from decoding transformer DT.

The code responsive device SR comprises a magnetizable core 15 upon which are disposed an output winding 16, a biasing winding 17 and a control winding 18. The biasing winding 17 is constantly supplied with unidirectional current from a suitable source, such for example as a rectifier R1 which has its output terminals connected to winding 17 and has its input terminals connected across the secondary winding of a transformer T1. The primary winding of transformer T1 is connected across a source of alternating current designated by the reference characters BX and CX, and it follows that winding 17 is constantly energized to create unidirectional flux of a given polarity in core 15 to set up a given flux condition in such core. I have represented graphically in Fig. 4 the flux condition established in core 15 by the flux due to current in winding 17, and I shall refer to this biasing flux as being flux of normal polarity and the magnetic condition set up in core 15 by such flux as being the normal flux condition of device SR.

The control winding 18 of device SR is supplied with energy derived from the track rails 1 and 1a for varying the magnetic condition of core 15 in step with the supply of such energy. As shown, energy from the rails 1 and 1a is supplied to winding 18 through the medium of a receiving transformer RT, which has its primary winding connected across the track rails of section D—E adjacent the entrance end D and has its secondary winding connected to the input terminals of a rectifier R2, the output terminals of this rectifier being connected to winding 18. It is readily apparent that the alternating energy supplied to the track rails 1 and 1a is rectified by rectifier R2 into and is supplied to winding 18 as unidirectional current. The curve shown in Fig. 3 represents the rectified current supplied from rectifier R2 to winding 18 in response to the supply of 120 code energy to the rails of section D—E, and since such energy sets up a unidirectional flux in core 18 proportional to the ampere turns of winding 18, such curve also represents the flux created in core 15 due to the supply of such energy to winding 18.

The connection of winding 18 to rectifier R2 is selected in such manner that the flux created in core 15 due to current in winding 18 opposes the flux due to current in winding 17. Preferably, the parts of winding 18 are selected and designed so that when unidirectional energy of a

predetermined magnitude is supplied to winding 18, the normal flux created by winding 17 is entirely neutralized and a resultant flux condition is established in the core of substantially equal density and opposite relative polarity to that of the normal flux condition. The curve shown in Fig. 5 represents a typical variation of the magnetic condition of core 15 caused by the supply of biasing flux and of control flux to such core. In Fig. 5, it is assumed that control flux is supplied to core 15 in response to the supply to winding 18 of the 120 code control energy, such as is represented in Fig. 2.

In Fig. 1, the biasing winding 17 and control winding 18 are illustrated controlling the magnetic condition of a saturable reactor type code responsive device, hence the magnetizable core 15 of device SR is illustrated as comprising, as is the usual practice, a three-legged structure having biasing winding 17 and control winding 18 disposed on the middle leg of the core and an output winding comprising two coils 16, 16 disposed one on each of the two outer legs of the core. The two coils 16, 16 of the output winding are connected together in series to a source of alternating current, and it follows that the impedances of the two coils comprising the output winding of device SR are varied in step with the variations of the magnetic condition of core 15. Preferably, the connection of the two coils 16 of winding 16 is such that both coils cooperate in circulating a flux in agreement in the two outer legs of core 15, and as a result substantially no alternating flux traverses the middle leg of core 15 so that no alternating current components are induced in windings 17 and 18. It is readily apparent that by properly proportioning and designing the parts of reactor SR, the magnetizable core 15 may be normally held at a given flux condition (preferably being held at a saturated condition), in response to the biasing flux created by winding 17 so that as a result the impedance of winding 16 is relatively low and current of relatively high magnitude flows through winding 16. When, however, control energy is supplied to winding 18, the flux due to current in winding 18 first carries the core through an unmagnetized or no-flux condition, wherein the impedance of winding 16 is greatly increased and the current flow in such winding 16 is decreased to a relatively low value, to a resultant flux condition of substantially equivalent or saturated density of flux of opposite relative polarity, wherein the current flow in winding 16 again reaches its normally high value. On the interruption of current to winding 18, a similar variation in flux condition of the core is established with a corresponding variation in magnitude of current traversing winding 16. The curve illustrated in Fig. 6 represents the effective current flow in winding 16 of device SR under the conditions wherein 120 code is supplied to control winding 15 of the device. It is to be noted from Fig. 6 that the number of code impulses supplied from output winding 16 of device SR per unit of time is double the number of code impulses supplied to winding 18 in the same interval of time (see Fig. 3), hence it follows that device SR functions to increase the code rate or frequency at which energy is supplied to its associated decoding apparatus in response to the supply of coded control energy to device SR.

It should be pointed out that by means of biasing winding 17, energy supplied through

winding 16 under the influence of coded current in winding 18 is caused to be coded at a rate double the code rate of energy supplied to winding 18, whereas if biasing winding 17 is not employed, the coding of current in winding 16 caused by the supply of coded current to winding 18 results merely in reproducing in winding 16 the coding of the current in winding 18. This follows from the fact that if only winding 18 were employed, the reluctance of core 15 then would vary from a relatively high value to a relatively low value in step with the supply of current to winding 18 and current in winding 16 accordingly would vary in step with the supply 15 of the coded impulses of current in winding 18. The effective current in winding 16 under such assumed conditions would, therefore, be represented by a curve substantially similar to that shown in Fig. 2. When, however, biasing winding 17 is employed to set up an initial or normal flux in core 15, the supply of current to winding 18 then causes the reluctance of core 15 to vary from a relatively high value to a relatively low value twice for each impulse of code supplied to winding 18, and as a result current in winding 16 is caused to be coded at a rate double the rate at which current supplied to winding 18 is coded.

As shown in Fig. 1, output winding 16 of device SR supplies energy to a portion of the primary winding of a decoding transformer DT through the medium of a transformer T2 and a rectifier R3, which rectifier is connected to cause energy supplied from winding 16 to create in 30 its associated portion of the decoding transformer a flux which opposes the flux normally created in the remainder of the primary winding by energy supplied from a rectifier R4 constantly connected through a transformer T3 to 35 a source of alternating current. Preferably, the parts of decoding transformer DT are so designed and proportioned that a predetermined density of magnetic flux of one polarity is set up in the core of transformer DT by the constant supply of energy from rectifier R4, and such magnetic flux is entirely neutralized and a resultant magnetic flux of substantially equal density but of opposite relative polarity is created in the core of transformer DT on the supply 40 of energy from device SR. It can be seen, therefore, that the magnetic condition of transformer DT is carried from a given flux condition through its zero or no flux condition to a substantially equivalent flux condition of opposite 45 relative polarity both on the supply and on the interruption of energy from device SR so that an electromotive force is induced in the secondary winding of transformer DT due to the variations in flux in the transformer core.

The secondary winding of transformer DT is connected to supply energy to suitable decoding apparatus, which apparatus includes the usual decoding relays one for each of the plurality 50 of code rates supplied to the rails of the trackway, whereby selective control of traffic governing signal S is established in accordance with the rate at which control energy is supplied to device SR. As shown, signal S is controlled to 55 one or another of a plurality of distinctive signal aspects through the medium of three decoding relays AJ1, BJ1 and HI one for each of the three assumed rates of coding, and which relays are coupled with the secondary winding 60 of transformer DT through the medium of suit-

able decoding or code distinguishing units DU1, DU2 and DU3, respectively.

The details of construction of the decoding units DU1, DU2 and DU3 are not shown in the drawings, but such units usually comprise a rectifier and a reactor condenser tuning unit tuned to resonance respectively at a frequency corresponding to a predetermined multiple of the 180, 120 and 75 code rates supplied to the track rails, whereby relays AJ1, BJ1 and HI are effectively energized and picked up when and only when the predetermined multiple of its associated control code, at least, is supplied from decoding transformer DT to such relay. That is to say, the construction and design of the decoding units DU preferably are such that relay HI is energized by current supplied through decoding unit DU3 when transformer DT supplies the predetermined multiple of the 75 code; relay BJ1 is energized by current supplied through decoding unit DU2 when transformer DT supplies the predetermined multiple of the 120 code; and relay AJ1 is energized by current supplied through decoding unit DU1 when and only when transformer DT supplies the predetermined multiple of the 180 code to such relay.

The operation of the apparatus of Fig. 1 is as follows: the rails of section D—E are supplied with control energy of 180, 120 or 75 code in accordance with traffic conditions in advance of 30 the section, and when section D—E is unoccupied, this control energy is supplied from the rails of section D—E to device SR. The parts of the apparatus which supply control energy to and which receive control energy from the track 35 rails are designed and proportioned so that under the most unfavorable ballast conditions expected to be met in practice, energy of a predetermined magnitude is supplied to device SR sufficient, at least, to create in core 15 of device 40 SR a resultant flux condition substantially equivalent in magnitude and opposite in relative polarity to the given normal flux condition established in the core of device SR due to current 45 constantly supplied to biasing winding 17.

If the rails of section D—E are supplied with 50 180 code and the section is unoccupied, then device SR functions in response to energy received by winding 18 from section D—E to supply energy of double the rate or 360 code to transformer DT. This supply of energy of double rate or 360 code to transformer DT causes induced electromotive forces to be supplied from the secondary winding of the transformer and as a result 55 relay AJ1 is energized and signal S is caused to display its "clear" aspect over a circuit extending from one terminal B of a suitable source of current, such as a battery not shown, through front contact 21 of relay AJ1 and the filament of signal unit G of signal S to the other terminal 60 C of the source of current. Under the assumed conditions of code in the trackway, it is immaterial whether or not relays BJ1 and HI are also picked up since at this time these latter relays 65 do not exert a control over signal S, but if the decoding units DU are high-pass filters, relays BJ1 and HI also will be picked up, as shown in Fig. 1, in response to the current that is supplied from transformer DT.

If, now, 120 code is supplied to the rails 1 and 1a and it is received by the code responsive device SR, such device functions to supply energy of double code rate or 240 code to transformer DT, which transformer in turn supplies the current caused to be induced in its secondary wind- 75

ing to the relays AJ1, BJ1 and HI. By virtue of the construction and arrangement of the decoding units DU, relay AJ1 is released but relay BJ1 is picked up in response to the current caused to be supplied from transformer DT under the assumed conditions of 120 code in the track rails, so that as a result signal S is controlled to display its "approach medium" aspect over a circuit extending from terminal B through back contact 22 of relay AJ1, front contact 23 of relay BJ1 and the filaments of signal unit Y/G of signal S to terminal C.

In the event that 75 code is supplied to the rails of section D—E and is received by device SR, then such device functions to supply energy of a double rate or 150 code to transformer DT, and such transformer supplies relays HI, AJ1 and BJ1 with the current caused to be induced in transformer DT due to the supply of 150 code. As pointed out heretofore, the decoding units DU function in such manner that only relay HI is picked up in response to the supply of the predetermined multiple of 75 code, and as a result signal S is controlled to its "approach" aspect over a circuit which passes from terminal B through back contact 22 of relay AJ1, back contact 24 of relay BJ1, front contact 25 of relay HI and the filament of unit Y of signal S to terminal C.

If, however, section D—E is occupied so that the control energy supplied to its rails is shunted away from device SR, then the impedance of winding 16 of such device is constantly held at a low value by the biasing flux present in core 15, and as a result a constant value of alternating current is supplied to rectifier R3, which functions to rectify such current into unidirectional current and supply such unidirectional current to transformer DT. Both portions of the primary winding of transformer DT are thus constantly supplied with unidirectional current to establish a steady condition of magnetic flux in transformer DT. As a result, therefore, no transformer action is effected by this flux so that relays AJ1, BJ1 and HI are all released and signal S is caused to display its "stop" aspect over a circuit extending from terminal B through back contact 22 of relay AJ1, back contact 24 of relay BJ1, back contact 26 of relay HI and the filament of unit R of signal S to terminal C.

From the foregoing description of the operation of the apparatus of Fig. 1, it is readily apparent that I have provided novel and improved control apparatus of the static type involving no moving parts and responsive to control code for proportionately increasing or multiplying the code rate at which energy is supplied to control apparatus from the device in response to the supply of coded energy to such device.

It is to be understood, of course, that the particular construction of the code responsive saturation device SR shown in Fig. 1 is merely illustrative, and that such device may take other suitable forms wherein the supply of energy from an output winding is controlled by a magnetizable core in which the flux in a portion, at least, of such core varies between a given flux condition and a substantially equivalent resultant flux condition of opposite relative polarity both on the supply and on the interruption of control energy to such device. For example, the code responsive device may take the form of a saturable transformer wherein the inductive coupling between a primary winding constantly sup-

plied with alternating current and an output winding is controlled by varying the relative reluctances or flux conditions of different portions of a magnetizable core which carries such primary and output windings.

In addition, it is to be understood that although the apparatus embodying my invention has been illustrated and described as applied to the control of a wayside signal, such apparatus may if desired be carried on a train to control a train-carried control device in response to control energy inductively received from the rails of a trackway.

Although I have herein shown and described only one form of code responsive control apparatus embodying my invention, it is understood that various changes and modifications may be made therein within the scope of the appended claims without departing from the spirit and scope of my invention.

Having thus described my invention, what I claim is:

1. In combination with a pair of conductors supplied at times with energy coded at one or another of a plurality of code rates in accordance with certain predetermined conditions, a magnetizable core having means for establishing in said core a normal flux condition of given density and relative polarity, a control winding disposed on said core, means for supplying from said conductors to said control winding energy of a predetermined magnitude and polarity for establishing in said core a resultant flux condition substantially equivalent in density and opposite in relative polarity to said given flux condition, an output winding disposed on said core, and a source of alternating current coupled through said output winding to decoding apparatus selectively responsive to the rate at which energy is supplied thereto.

2. In combination with a source of current having means for periodically interrupting or coding such current at one or another of a plurality of code rates, two magnetizable cores each having means for establishing in its respective core a normal flux condition of given density and relative polarity, two control windings one disposed on each core, means for supplying from said source to a first of said control windings current of a magnitude and polarity selected to establish in its associated first core a resultant flux condition substantially equivalent in density and opposite in relative polarity to said normal flux condition, an output winding disposed on said first core and connected to the other of said two control windings for supplying to said other control winding current of a predetermined magnitude and polarity effective to establish in the other of said two cores a resultant flux substantially equivalent in density and opposite in relative polarity to said normal flux condition, another output winding disposed on said other core, and control means receiving energy from said other output winding and selectively responsive to the form of energy supplied thereto.

3. In combination with a source of current having means for periodically interrupting or coding such current at one or another of a plurality of code rates, two magnetizable cores each having means for establishing in its respective core a normal flux condition of given density and relative polarity, two control windings one disposed on each core, means for supplying from said source to a first of said control windings unidirectional current of a magnitude and polarity

selected to establish in its associated first core a resultant flux condition substantially equivalent in density and opposite in relative polarity to said normal flux condition, an output winding disposed 5 on said first core, a rectifier, a source of alternating current coupled through said output winding and said rectifier to the other of said two control windings in such manner as to supply unidirectional current of a predetermined 10 magnitude and polarity to said other control winding for establishing in its associated other core a resultant flux substantially equivalent in density and opposite in relative polarity to said normal flux condition, another output winding 15 disposed on said other core, and control apparatus connected to receive current induced in said other output winding and selectively responsive to the rate at which such current is varied.

4. In combination with a pair of conductors supplied at times with energy coded at one or another of a plurality of code rates in accordance with certain predetermined conditions, a magnetizable core, means for supplying magnetic flux of a given polarity to said core for normally establishing 20 a given flux condition in said core, a control winding disposed on said core and proportioned in such manner that when supplied with unidirectional energy of a predetermined magnitude and polarity said winding supplies flux of 25 the opposite relative polarity to said core for establishing in said core a resultant flux condition opposite in relative polarity but substantially equivalent in density to said given flux condition, means for supplying said control winding 30 with energy of said predetermined magnitude and polarity derived from said pair of conductors for energizing said control winding in step with the supply of energy to said conductors, an output winding disposed on said core and receiving energy 35 from a source of alternating current under the influence of the magnetic flux in said core, and control apparatus controlled by energy supplied from said output winding and selectively responsive to the rate at which such energy is 40 coded.

5. In combination with a stretch of railway track having two conductors governed by traffic conditions on said stretch and having means for supplying to said conductors energy which is coded at one or another of a plurality of code 45 rates in accordance with traffic conditions in advance, a magnetizable core, means for supplying to said core magnetic flux of a given polarity for normally establishing a given flux condition in said core, a control winding disposed on said core and proportioned in such manner that when supplied with unidirectional current of a predetermined magnitude and polarity said winding supplies flux of the opposite relative polarity 50 to said core for creating in said core a resultant flux condition opposite in relative polarity but substantially equivalent in density to said given flux condition, means for supplying said control winding with unidirectional current of said predetermined magnitude derived from said two conductors for energizing said control winding in step with the supply of energy to said conductors, an output winding disposed on said core and receiving energy from a source of alternating current 55 under the influence of the magnetic flux in said core, and railway traffic controlling apparatus selectively controlled by energy supplied from said output winding in accordance with the rate at which such energy is coded for governing traffic 60 on said stretch.

6. In combination with a stretch of railway track having means for supplying coded trackway energy to the rails of said stretch, a magnetizable core normally held at an initially saturated condition by flux of a given polarity, a control winding disposed on said core, means for supplying unidirectional energy of a predetermined magnitude and polarity from the rails of said stretch to said control winding for saturating said core with resultant flux of the opposite 10 relative polarity, an output winding disposed on said core and receiving energy from a source of alternating current under the influence of the magnetic flux in said core, and railway traffic controlling apparatus selectively responsive to the code rate at which current is supplied to such apparatus from said output winding for controlling traffic on said stretch.

7. In combination with a stretch of railway track having means for supplying coded trackway energy to the rails of said stretch, a magnetizable core normally held at an initially saturated condition by flux of a given polarity, a control winding disposed on said core, means for supplying unidirectional energy of a predetermined magnitude and polarity from the rails of said stretch to said control winding for saturating said core with resultant flux of the opposite relative polarity, a source of alternating current, railway traffic controlling apparatus for controlling traffic on said stretch and selectively responsive to the code rate at which current is supplied thereto, and an output winding disposed on said core for coupling said source to said control apparatus whereby such apparatus is supplied with 35 coded current from said source in response to the flux conditions in said core.

8. In combination with a stretch of railway track having means for supplying to the track rails of said stretch trackway energy which is coded at one or another of a plurality of different rates of coding, a magnetizable core provided with means for supplying flux of a given polarity to said core for establishing a flux condition of given density in said core, a control winding disposed on said core and proportioned in such manner that when supplied with unidirectional energy of a predetermined polarity and magnitude said winding supplies to said core flux of the opposite relative polarity and of such magnitude that a resultant flux condition substantially equal in density and opposite in relative polarity to said given flux condition is created in said core, means responsive to said trackway energy for supplying to said control winding unidirectional energy of said predetermined polarity and magnitude, an output winding also disposed on said core, and railway traffic controlling apparatus controlled by energy supplied from said output winding and selectively responsive to the coding 55 of such energy as effected by the varying flux conditions in said core.

9. In combination with a stretch of railway track having means for supplying to the track rails of said stretch trackway energy which is coded at one or another of a plurality of different rates of coding, a magnetizable core provided with means for supplying flux of a given polarity to said core for establishing a given flux condition in said core, a control winding disposed on said core, means responsive to said trackway energy for supplying to said control winding unidirectional energy of a predetermined polarity and magnitude for creating in said core a resultant flux condition substantially equivalent in density 75

- and opposite in relative polarity to said given flux condition, an output winding also disposed on said core, a source of alternating current, decoding means supplied with energy from said source through said output winding and selectively responsive to variations in such energy as effected in response to varying impedance conditions of said output winding caused by varying flux conditions in said core, and railway traffic controlling apparatus selectively controlled by said decoding means for controlling traffic in said stretch.
10. In a code control system of the class wherein coded current supplied from a control circuit selectively controls code responsive control apparatus in accordance with the rate at which such current is coded, the combination with said circuit and said control apparatus of a code repeating device receiving from said circuit current coded at one or another of a plurality of code rates and supplying current to said control apparatus at an increased rate of coding proportional to the rate at which the received current is coded, said device comprising a source of alternating current and a magnetizable core carrying an output winding coupled with said source and supplying current to said control apparatus, said core also having means for varying the flux in said core between flux conditions of substantially equivalent densities and of opposite relative polarities both on the supply and on the interruption of current to the device from said circuit, whereby the supply of current from said source to said control apparatus through said output winding is caused to be coded at a rate double the rate at which current is received by the device from said source.
11. In combination with decoding apparatus adapted to be selectively controlled in accordance with the rate of coding at which current is supplied from a control circuit, a magnetizable core, a source of alternating current coupled with an output winding disposed on said core for supplying current to said decoding apparatus, and means on said core responsive to current supplied from said control circuit for varying the magnetic flux in said core between flux conditions of substantially equivalent densities and of opposite relative polarities both on the supply and on the interruption of current from said control circuit.
12. In combination with decoding apparatus adapted to be selectively controlled in accordance with the rate of coding at which current is supplied from a control circuit, a magnetizable core, means on said core responsive to current supplied from said control circuit for varying the magnetic flux in said core between flux conditions of substantially equivalent densities and of opposite relative polarities both on the supply and on the interruption of current from said control circuit, and a source of periodically varying current connected through an impedance winding disposed on said core to said decoding apparatus.
13. In combination with decoding apparatus adapted to be selectively controlled in accordance with the rate of coding at which current is supplied from a control circuit, a magnetizable core, means on said core responsive to current supplied from said control circuit for varying the magnetic flux in said core between flux conditions of substantially equivalent densities and of opposite relative polarities both on the supply and on the interruption of current from said control circuit, and a source of alternating current coupled through a winding disposed on said core to said decoding apparatus for supplying such apparatus with current caused to be coded in response to variations of flux in said core.

CHARLES C. BUCHANAN. 40
